UNITED STATES PATENT OFFICE.

EDWARD W. DODGE, OF PORTLAND, MAINE.

DESIGN FOR STATUETTE.

Application filed September 25, 1923. Serial No. 7,310. Term of patent 7 years.

To all whom it may concern:

Be it known that I, EDWARD W. DODGE, a citizen of the United States, residing at Portland, in the county of Cumberland and State of Maine, have invented a certain new, original, and ornamental Design for Statuette, of which the following is a specification, reference being had to the accompanying drawing, forming a part thereof.

The figure of the drawing is a perspective view of my new design for statuette.

I claim:—

The ornamental design for statuette as shown.

EDWARD W. DODGE.
